TAG FASTENER

Samuel Weiss, Brooklyn, N. Y.

Application November 10, 1937, Serial No. 173,752

2 Claims. (Cl. 40—25)

My invention relates to improvements in tag fasteners and it consists in the novel features which are hereinafter described.

One of the objects of my invention is to provide a fabric tag with a perfected means for fastening the same to a garment or a piece of linen in a way to prevent the disengagement of the garment from the fastener.

Another object of my invention is to prevent the disengagement of the tag from the fastener.

A further object of my invention is to prevent the laceration of garments and of the hands of operators by the protrusion of sharp points from the fastener.

15 A still other object of my invention is to have my improved tag fastener adapted to be made by mass production methods.

A further object of my invention is to have said tag fastener simple, durable and inexpensive.

20 Other objects and advantages will hereinafter appear.

I attain these objects by the tag fastener, three forms of which are illustrated in the accompanying drawing, or by any mechanical 25 equivalent or obvious modification of the same.

In the drawing, Figs. 1, 2, 3, and 4 show one form of my tag fastener; Fig. 5 shows another form of my tag fastener, and Fig. 6 shows a third form of my tag fastener.

30 Fig. 1 is a section on the line 1—1 of Fig. 2, looking in the direction of the arrows; Fig. 2 is a side elevation, looking from left to right in Fig. 1, of one form of my tag fastener; and Fig. 3 is a side elevation, looking from the lower right hand end to upper left hand end of the fastener shown in Fig. 1, in a direction at right angles to the prong 12 thereof, which is hereinafter described, and omitting the tag.

Fig. 4 is a section on the line 4—4 of Fig. 3, 40 looking in the direction of the arrows.

Fig. 5 is a sectional view similar to that of Fig. 1, and showing another form of my invention; and Fig. 6 is another sectional view similar to those of Figs. 1 and 5 and showing a third form of my invention.

Similar numerals refer to similar parts throughout the several views:

In all the three modifications of my invention, 50 11 and 12 designate the two prongs or legs of my fastener which are shown as continuous with each other at the bend 13. The leg 11 has a tag 14 secured thereto by means of an eyelet rivet 15 which is integral with the leg 11.

55 A piercing tongue 16 is slotted from the body

of the leg 11, as at 17, and is disposed to meet an opening 18 in the leg 12, when the two legs or prongs are brought together, after passing the tongue 16 through part of a garment to which the tag 14 is to be fastened.

The outer end of the leg 12 at the opening 18 has thereon a portion which is bent to a double curvature at 20—21 as shown in Figs. 1, 5, and 6.

On passing the tongue 16 through the opening 18 in the leg 12, the legs 11 and 12 are pressed together, and the part of the tongue 16 which extends beyond the opening 18 in the leg 12 is bent into contact with the said portion 20—21, whereby the resistance to separation of the prong 11 and 12 is increased.

In the form of my invention which is shown in Figs. 1, 2, 3, and 4, the part of the leg 12 at the opening 18 is provided on the side thereof which is opposite the leg 11 with a depression 19 which serves to guide the end of the tongue 16 into the opening 18 when bringing the legs or prongs 11 and 12 together.

The leg 12 also has thereon on the side thereof, which is remote from the leg 11, a longitudinally disposed pocket 22 which serves to receive therein the end of the tongue 16 when the latter has been passed through the opening 18 and after it has been bent along the double-curved portion 20—21 on the leg 12 as hereinbefore described.

The pocket 22 is instrumental in preventing the laceration of garments and the hands of operators by the end of the tongue 16; and the longitudinal disposition of the pocket 22 enables the prongs or legs 11 and 12 to be relatively narrow, thereby saving metal and assisting in rendering my tag fastener inexpensive.

In the modification of my tag fastener, which is shown in Fig. 5, the feature of the depression 19 is omitted for the sake of economy in manufacturing the fastener, but the other above described features are retained.

In the form of my invention, which is shown in Fig. 6, both the depression 19 and the pocket 22 are omitted, thereby still further reducing the cost of manufacturing of the fastener; but the feature of the double curved portion 20—21 on the leg 12 is retained and the outer end of the leg 12 is offset from the plane of the main body 50 of the leg 12.

Variations are possible, and parts of my invention may be used without other parts; I do not, therefore, restrict myself to the details as shown in the drawing.

I claim as my invention and desire to secure by Letters Patent:—

1. A tag fastener made of sheet metal and having thereon a pair of legs and a tag attached to one of said legs, a piercing tongue on one of the said legs for attaching the same to a garment, an opening in the other leg for said tongue to pass therethrough, to secure said legs to each other during the operation of attaching the fastener to a part of a garment, and a portion on said other leg adjacent to said opening, having thereon an outwardly convex part and an outwardly concave part adjoining the same, thereby forming a reverse curvature for bending thereon the said tongue exteriorly of said other leg to an inwardly extending offset after pressing the said two legs together with said garment part therebetween, and said other leg having thereon at the outer end thereof, on the side thereof which is opposite the first mentioned leg, a depression at said opening, for guiding the end of said tongue into the said opening during the operation of attaching the fastener to a garment.
2. A tag fastener made of sheet metal and hav-

ing thereon a pair of legs and a tag attached to one of said legs, a piercing tongue on one of the said legs, for attaching the same to a garment, an opening in the other leg for said tongue to pass therethrough, to secure said legs to each other during the operation of attaching the fastener to a part of a garment, and a portion on said other leg adjacent to said opening having thereon an outwardly convex part and an outwardly concave part adjoining the same, thereby forming a reverse curvature for bending thereon the said tongue exteriorly of said other leg to an inwardly extending offset after pressing the said two legs together with said garment part therebetween, and said outwardly concave part of said portion 15 on said other leg forming part of a longitudinally disposed pocket in the outer side of said other leg, said pocket serving for receiving therein the end of said tongue when said fastener has been attached to a garment, thereby preventing the 20 laceration of garments and the hands of operators by said tongue.

SAMUEL WEISS.
